CLAIM

The ornamental design for a mobile electric heater, as shown and described.

DESCRIPTION

FIG. 1 is a perspective view of a mobile electric heater; FIG. 2 is a front view of the mobile electric heater of FIG. 1;

FIG. 3 is a rear view of the mobile electric heater of FIG. 1; FIG. 4 is a left side view of the mobile electric heater of FIG. 1;

FIG. 5 is a right side view of the mobile electric heater of FIG. 1;

FIG. 6 is a top view of the mobile electric heater of FIG. 1; and,

FIG. 7 is a bottom view of the mobile electric heater of FIG. 1.

The broken lines shown in the drawings are for the purpose of illustrating portions of the article and form no part of the claimed design.
